UNITED STATES PATENT OFFICE.

DAVID F. DOMIZI, OF CLEVELAND, OHIO.

HEATING OVEN.

Application filed December 7, 1922. Serial No. 605,536.

To all whom it may concern:

Be it known that I, DAVID F. DOMIZI, a citizen of the United States, residing at Cleveland, in the county of Cuyahoga and State of Ohio, have invented a certain new and useful Improvement in Heating Ovens, of which the following is a full, clear, and exact description.

This invention relates to heating ovens, 10 the particular installation shown herein being designed for use in connection with japanning apparatus.

It will be readily understood, however, that the principles of the invention are applicable to the heat treatment of materials 15 generally, the modifications in structure and temperature conditions necessary for the various heat treating processes being obvious to those skilled in the art.

20 An object of the invention is to provide an oven of the type in which articles are continuously conveyed therethrough in which there is a minimum waste of heat due to the passage of the articles to and from the oven and in which the handling of the 25 articles outside the oven is facilitated.

A further object is to provide efficient means for heating the various compartments 30 of the oven so as to provide gradual heating of the articles entering the oven and gradual cooling of articles leaving the oven.

A further object is to provide economical and efficient means for maintaining different temperatures in the various compartments 35 of the oven.

A further object is to provide automatic means responsive to the heat within the oven for regulating the temperature of the oven.

40 A further object is to provide an installation in which a minimum amount of floor space is occupied and in which it is possible to load and unload articles from the oven conveyor upon different floors of the building.

45 Other objects will be apparent from the following description and accompanying drawings.

The following description and accompanying drawings set forth in detail certain means embodying my invention, the disclosed means, however, constituting but one of the various mechanical forms in which the principles of the invention may be employed.

50 Reference should be had to the accompanying drawings in which Fig. 1 is a longitudi-

nal vertical section through the oven and Fig. 2 is a vertical transverse section through the oven.

Referring to the accompanying drawings, 60 the oven is a rectangular box-like structure having a horizontal bottom wall 1, vertical side walls 2 and 3, front and rear and end walls 4 and 5 and a horizontal top wall 6, each of the walls being preferably formed 65 of or covered with heat insulating material. Within the oven adjacent the rear wall 5 is a vertical transverse partition 7 also preferably formed of or covered with heat insulating material and extending from the bottom of the oven to a short distance below the top thereof. A horizontal partition 8 extends from the top of the vertical partition 7 to adjacent the front wall 4 of the furnace. The partition 8 is narrower than 70 the oven and the side edges thereof are spaced from the side walls 2 and 3 of the oven forming passages 9 at the edges of the partition 8, permitting free flow of gases from the compartment beneath the partition 8 to the upper compartment of the oven. The end of the partition 8 adjacent the front wall 4 of the oven terminates short of 75 the front wall to provide a conveyor passage 10 to the uppermost compartment. An intermediate horizontal partition 11 below the partition 8 extends from the front wall 4 rearwardly to adjacent the vertical partition 7 and has spaces 12 between its 80 opposite side edges and the side walls 2 and 3 of the oven similar to the side openings 9 along the edges of the partition 8. The intermediate partition 11 terminates short of the front oven wall 4 and the vertical partition 7 at the rear end of the furnace 85 to provide an opening 13 at the front end thereof and an opening 14 at the rear for the passage of the conveyor. The horizontal partitions 8 and 11 divide the oven into three superposed horizontally extending compartments 15, 16 and 17; 15 being the lowermost compartment, 16 the intermediate compartment and 17 the uppermost compartment. The lowermost compartment 15 has inclined at its forward end a wall 18 formed 90 of heat insulating material and extending upwardly from the bottom wall 1 at the front end of the furnace and rearwardly to adjacent the vertical partition 7 at the rear end of the furnace. Between the inclined wall 18 and the bottom wall 1 of the furnace 95 is formed an expansion chamber 19 from 100 105 110

which heated air is supplied to the interior of the oven. The lower compartment 15 has a sheet metal liner or drip pan 18^a over the bottom wall 18 and spaced therefrom. At the rear end of the compartment 15 is an end plate 20 extending upwardly from the rear end of the wall 18 and spaced from the partition 7. The compartment 15 also has side wall plates 21 extending from the side edges of the bottom wall 18 of the compartment, said edges being spaced from the side walls 2 and 3 of the oven, and to the side edges of the intermediate partition 11. The lower compartment 15 is thus enclosed at its sides, bottom and rear end in a sheet metal casing, the walls of which are spaced from the side walls of the oven, the inclined wall 18 and the rear wall 7, forming end and side passages 22, 23, and 24 alongside the sides and ends of the lower compartment and opening into the bottom of the intermediate compartment 16. The two upper compartments are thus heated by means of hot air currents, while the lower compartment is heated by radiation through the sheet metal walls. The heat insulating wall 18 prevents excessive heating of the sheet metal bottom plate 18^a of the lower compartment. It is preferable, however, to supply some heat to the space between the wall 18 and the plate 18^a. For this purpose small passages 25 open into the space between the wall 18 and plate 18^a to permit some heated air to pass from the expansion chamber 19 to the space beneath the plate 18^a.

A suitable oil burning or gas furnace 26 is mounted within the expansion chamber 19. The outer end of the furnace 26 extends through the side wall of the oven and has an air inlet and burner receiving opening 27 in which is located a suitable jet burner 28. The furnace 26 has outlets 29 adjacent its bottom and communicating with the expansion chamber 19 through which the heated gases pass from the furnace into the expansion chamber. An additional air inlet opening 30 controlled by a valve 31 may be provided in the bottom 1 to admit additional air to the expansion chamber 19. In the top wall of the oven are spaced ventilating flues 32 and 33 provided with manually adjustable butterfly valves 34 and 35 which can be set at the desired angle to regulate the escape of gases from the top of the oven. At the center of the top wall 6 is the main outlet flue 36 which is controlled by a valve 37. The outlet valve 37 is preferably controlled automatically to vary the opening proportionately to the heat of the oven. The thermal controlling means for the valve 37 consists of a long metallic expansion rod 38 attached at its lower end to a fixed support on a side wall of the oven and at its upper end to a lever 39 pivoted

intermediate its ends to a bracket 40 secured to the top wall 6 and engaging at its inner end with a second lever 41 which in turn is pivoted intermediate its ends to a bracket 42 attached to the top wall 6 and at its inner end engages the stem 43 of the valve 37. The vertically disposed expansion rod 38 is expanded by the heat of the oven and acts through the levers 39 and 41 to elevate the valve 37. The parts will be so adjusted that when a predetermined temperature is reached in the oven the levers will begin to lift the valve 37 from its seat. As the temperature in the oven increases the opening past the valve 37 will be increased proportionately causing the temperature to be lowered and a drop in the temperature of the oven will result in a corresponding restriction of the outlet passage through the flue 36 to impede the outflow of heated gases and cause an increase in the temperature.

When the oven is used for japanning operations, the furnace 26 will be heated to approximately 1800°, maintaining a temperature in the expansion chamber 19 of approximately 500°. The heated gases will pass upwardly from the expansion chamber 19 along the side walls of the furnace into the intermediate and upper compartments 16 and 17. Since there is a free passage along the side walls to the upper compartment 17 the upper compartment will be heated to a higher temperature than the intermediate compartment 16, the upper compartment having an average temperature around 450° and the intermediate compartment having a temperature around 300°. The lower compartment 15 will be at a still lower temperature since it is heated by radiation only and its temperature will also be lower toward the front end of the oven through which the conveyor enters due to the entry of air through the conveyor entrance opening. The temperature of the central portion of the lower compartment, however, will be around 250°. In heat treating operations such as in japanning a certain amount of heavy gaseous products are formed. These heavy gaseous products naturally settle to the bottom of the oven and would pass out through the conveyor entrance opening unless special means were provided for conducting these gases away. In the present invention these heavier gases can pass freely from the upper compartments into the lower compartments through the openings 13 and 14 in the partition 11 adjacent the opposite ends thereof. To remove these heavy gases from the oven a light suction fan 44 communicates through the front wall 4 of the oven with the interior of the lower compartment 15 and discharges the gases through a suitable conduit.

The bottom wall 1 of the oven is pref

erably located at some distance above the first floor 45 of a building to provide a space for workmen beneath the oven and extends upwardly through one or more of the 5 upper floors of the building, the second floor 46 of the building being located somewhat above the bottom of the oven. An endless conveyor 47 provided with spaced hangers 48 is employed to carry the articles 10 through the oven, the oven being provided with an entrance opening 49 at the bottom of the front wall 4 and at the front end of the lower compartment 15 and an exit opening 50 being provided in the lower portion 15 of the rear wall 5. The endless conveyor 47 has a lower run which extends beneath the oven adjacent the bottom wall 1 and is guided adjacent the entrance opening over 20 guide sprockets 51 and 52 located adjacent the top and bottom respectively of the entrance opening 49. The conveyor passes rearwardly through the lower compartment 15 around a guide sprocket 53 in the conveyor opening 13, then into the intermediate compartment 16 and over a guide sprocket 54 adjacent the top thereof, then forwardly through the compartment 16 around a guide sprocket 55 in the conveyor opening 10 leading to the upper compartment, thence upwardly over a guide sprocket 56 adjacent the top wall 6 of the oven, rearwardly through the top compartment 17 over a guide sprocket 57 at the rear end thereof and downwardly through a vertical 35 passage 58 between the vertical partition 7 and rear wall 5 of the oven to adjacent the top of the exit opening 50 where it passes over guide sprockets 59 and 60 on the inner and outer sides of the rear wall 5. After emerging from the oven the conveyor 40 passes upwardly around the sprocket 60 and rearwardly over a guide sprocket 61 to a guide sprocket 62 in horizontal alignment with the guide sprocket 61 over the guide sprocket 62 and around a sprocket 63 beneath the sprocket 62 forwardly over a sprocket 64 in horizontal alignment with the sprocket 63. The sprockets 63 and 64 are located above the second floor 46 of the building 45 and provide a horizontal run above the floor 46 where articles may be loaded upon the conveyor. The conveyor passes downwardly from the sprocket 64 and around a drive sprocket 65 which is driven by a suitable motor 66 and is in horizontal alignment with the guide sprocket 51 at the bottom of the entrance opening 49. The lower run of the conveyor is directly beneath the oven and extends from the rear to the front thereof and is at a sufficient height from the floor 45 for convenient loading of the conveyor from the floor 45 adjacent the rear end of the horizontal run. Adjacent the rear end of the oven and beneath the lower run of the conveyor are two elevating dipping

tanks 67 and 68 which are alternately elevated to submerge the articles carried by the conveyor in the coating liquid contained in the tanks. Between the dipping tanks and the entrance opening 49 the lower 70 run of the conveyor has a comparatively long space in which the coating liquid may drip from the articles so that when the articles enter the oven the greater part of the excess liquid will have dripped off, however, any excess liquid on the articles may drip upon the inclined bottom plate 18^a of the lower compartment 15 which is at sufficient 75 inclination to permit the liquid to drain freely from the oven.

I do not confine myself to the particular heating means herein disclosed for as far as certain features of my invention are concerned, other suitable means for supplying the heat may be employed.

Having described my invention, I claim:

1. In an apparatus of the character described, an oven having a plurality of superposed compartments, an endless conveyor for conveying articles through the oven, and supports for said conveyor by which the latter is caused to travel back and forth through the compartments of the oven, said conveyor leading into the lowermost compartment at one end of the oven and out from the lower portion of the oven at its opposite end.

2. In an apparatus of the character described, an oven having a plurality of superposed compartments, and a passageway leading downwardly from the uppermost compartment, said oven having entrance and exit openings in lower portions thereof at its opposite ends, one opening communicating with the lowermost compartment and the other communicating with said vertical passageway, and means for conveying articles into the oven at one end through the opening therein into the lowermost compartment, forward and back 100 through the compartment successively from the bottom to the top, through the end passageway at the opposite end of the oven and out through the exit opening in the oven at the lower end of said passageway.

3. In an apparatus of the character described, the combination with an oven having a plurality of superposed horizontally disposed compartments, and a vertical passageway at one end of the oven leading downwardly from the uppermost compartment, said oven having conveyor entrance and exit openings in the lower portions thereof at its opposite ends, one of said openings communicating with the lowermost of said compartments and the other of said openings communicating with said vertical passageway, of an endless conveyor having one run thereof guided through the openings in the oven wall, the successive com-

- partments and end passageway, the other run of said conveyor extending from one end of said oven to the other outside said oven.
5. In an apparatus of the character described, an oven having its bottom supported above one floor of a building to provide a working space beneath said oven, said oven extending up through one or more upper floors of the building, and said oven having a plurality of superposed substantially horizontal compartments therein and conveyor entrance and exit openings at opposite ends thereof adjacent its bottom, and 10 an endless conveyor having a run thereof supported for movement through the entrance opening at one end of the oven back and forth through said compartments and out through the exit opening at the opposite 15 end of the oven, said conveyor having a return run beneath the oven and above said first floor of the building.
5. In an apparatus of the character described an oven having its bottom supported above one floor of a building to provide a working space beneath said oven, said oven extending up through one or more upper floors of the building and having superposed substantially horizontal compartments 20 therein, and an endless conveyor having a run thereof supported for movement into the lowermost compartment at one end of the oven, back and forth through said compartments from the bottom to the top 25 of the oven and out through an exit opening in the lower portion of the oven at the end opposite the entrance opening said conveyor having a portion outside the exit opening above the upper floor of the building 30 to permit unloading on said upper floor when desired and a return run extending beneath said oven and above said first floor whereby articles can be transferred from 35 said floor beneath said conveyor to said conveyor.
6. In an apparatus of the character described, an oven having a plurality of superposed substantially horizontal conveyor compartments and conveyor entrance 40 and exit openings in the lower portion thereof, a conveyor for carrying articles through said entrance opening back and forth through said compartments and out 45 said exit opening, said oven having a heating compartment beneath the lowermost of said conveyor compartments, the side walls and an end wall of said lowermost conveyor compartment being spaced from the side and end walls of the furnace forming an 50 open passage communicating with the heating compartment, said passage opening into the lower portion of an upper compartment, and means for conducting gaseous products 55 from said oven.
- 65 7. In an apparatus of the character de- scribed, an oven having upper and lower substantially horizontal conveyor compartments, a conveyor entrance opening communicating with one end of the lowermost compartment, and a conveyor exit opening in 70 the lower portion of the oven communicating with the upper compartment, a conveyor guided for movement through the entrance opening back and forth from end to end in 75 said compartments and out the exit opening, the upper compartment communicating with the lower compartment at the end adjacent the entrance opening for the passage of heavier gaseous products therefrom into the lower compartment and means adjacent 80 the exit opening for withdrawing the heavier gaseous products from the oven.
8. In an apparatus of the character described, an oven having a plurality of superposed compartments, means for conveying material back and forth through said compartments from the bottom to the top 85 thereof, means for heating one of the lower compartments by radiation through the walls thereof, and means for heating an 90 upper compartment by introducing heated gases thereinto.
9. In an apparatus of the character described, an oven having superposed horizontally extending compartments, means for conveying articles into and out of the oven and through said compartments successively, the upper compartment being in communication with said lower compartment at both 95 ends to permit free passage of heavier gaseous products to said lower compartment, and means for withdrawing said heavier gaseous products from said lowermost compartment.
10. In an apparatus of the character described, an oven having superposed horizontally extending compartments, means for conveying articles into and out of said oven and back and forth through said compartments successively, an expansion chamber 100 beneath the lower of said compartments, means for maintaining a supply of heated gas in said chamber, a heat insulating wall between said expansion chamber and the compartment above the same, sheet metal walls spaced from the walls of the oven at the sides of said lower compartment, the spaces between the oven walls and sheet metal walls opening into said expansion chamber and into the compartment above 110 said lower compartment.
11. In an apparatus of the character described, an oven having superposed compartments separated by horizontal partitions, the edges of said partitions being spaced from the side walls of said oven, the lowermost compartment having side walls spaced from the side walls of the oven and a heat insulating bottom wall, an expansion chamber 115 beneath the lowermost compartment com-
- 120
- 125
- 130

- communicating with the spaces between the side walls of said compartment and the oven walls and means for maintaining a supply of heated air in said chamber, said heated air passing freely from said chamber through the spaces at the sides of said lowermost compartment into said upper compartments.
12. In an apparatus of the character described, an oven having superposed compartments separated by horizontal partitions and a conveyor entrance opening in its wall at one end of the lowermost compartment, successive partitions having openings at opposite ends for the passage of a conveyor, a conveyor guided for movement through the entrance opening back and forth through the compartments, a chamber for heated air beneath the lowermost compartment, said chamber having a heat insulated upper wall inclined upwardly from the entrance opening, a sheet metal bottom plate in said lowermost compartment spaced above said heat insulated wall, and passages from said chamber to upper compartments of the oven and from said chamber to the space between the top wall of the chamber and the bottom plate of said lowermost compartment.
13. In an apparatus of the character described, an oven having superposed compartments, said oven having an opening in its wall at one end of the lowermost compartment and a vertical passageway leading from the uppermost of said compartments downwardly to an exit opening in the lower portion of the oven at the end opposite said entrance opening, said passageway being separated from the ends of said compartments by a heat insulating wall, means for conveying articles through said entrance opening back and forth through said compartments from the bottom to the top and out said exit opening, and means for heat-
- ing said compartments and maintaining progressively higher temperatures in successive compartments from the bottom to the top of the oven.
14. In an apparatus of the character described, an oven having superposed compartments, said oven having an opening in its wall at one end of the lowermost compartment and a heat insulating partition adjacent the end of the oven opposite the entrance extending from the uppermost compartment to adjacent the bottom of the oven and forming a passageway from the uppermost compartment to an exit opening in the lower portion of the oven, said lowermost compartment being enclosed in a sheet metal casing having its bottom and side walls spaced from the bottom and side walls of the oven and an end wall spaced from said partition, a chamber for heated air beneath said lowermost compartment, said chamber being in open communication with the spaces at the sides and end of said lowermost chamber and through said spaces with the upper compartments, and means for conveying articles into said oven back and forth through the compartments from the bottom to the top, through the passageway and exit opening.
15. In a device of the character described, an oven having superposed horizontally disposed compartments, and conveyor entrance and exit openings in the lower portion thereof, and endless conveyor having a portion guided through said entrance and exit openings and back and forth through said compartment, loading and unloading platforms at different levels outside said furnace, said conveyor having portions extending along said platforms.

In testimony whereof, I hereunto affix my signature.

DAVID F. DOMIZI.
